UNITED STATES PATENT OFFICE.

JAMES W. SNELL, OF LYNN, MASSACHUSETTS, ASSIGNOR TO VICTOR N. COX, OF LYNN, MASSACHUSETTS.

MACHINE FOR CHAMFERING THE HEELS OF BOOTS OR SHOES.

SPECIFICATION forming part of Letters Patent No. 772,541, dated October 18, 1904.

Application filed July 14, 1902. Serial No. 115,400. (No model.)

To all whom it may concern:

Be it known that I, JAMES W. SNELL, a citizen of the United States, residing at Lynn, in the county of Essex and State of Massachusetts, have invented new and useful Improvements in Machines for Chamfering the Heels of Boots or Shoes, of which the following is a specification.

The object of this invention is to provide a machine for chamfering or skiving a curved depression in the bottom lift of a heel upon the side of said lift adjacent to the breast of the heel, said depression in the heel being provided in order that when the heel is attached to the shoe the straight edge of the bottom lift may not cut into the sole of the shoe. Heretofore it has been the custom to form said depression in the bottom lift of the heel by compressing the same, requiring a powerful and expensive machine for the purpose.

The object of this invention is also to provide a machine for the purpose specified which may be adjusted so as to make depressions of different depths and lengths.

The invention consists, in a machine of the character described, of a rotary cutter, a work-support, and a breast-gage fast to said work-support, said work-support being provided with a supporting-surface for the bottom lift of the heel, said surface lying in a plane outside the periphery of said cutter.

The invention again consists in the instrumentalities hereinbefore set forth in combination with means for adjusting the work-support with relation to the rotary cutter, and, finally, the invention consists in the combination and arrangement of parts set forth in the following specification and particularly pointed out in the claims thereof.

Referring to the drawings, Figure 1 is an end elevation of my improved machine for chamfering the heels of boots and shoes. Fig. 2 is a side elevation of the same as viewed from the right of Fig. 1. Fig. 3 is a detail plan of the work-support together with the breast and side gages. Fig. 4 is a perspec-

tive view of a boot-heel, illustrating the work performed by my improved machine for chamfering the heels of boots and shoes.

Like numerals refer to like parts throughout the several views of the drawings.

In the drawings, 8 is the frame of the machine, provided with a base 9 and cap-bearings 10 10, in which a shaft 11 is journaled, said shaft being driven by a pulley 12, fast thereto. To one end of the shaft 11 is fastened a rotary cutter 13, said cutter consisting of a series of cutter-blades 14, the cutting edges of which are formed upon a curve preferably described from the center of the driving-shaft 11, Fig. 2. The boot-heel 7 when being operated upon is supported upon a work-support 15, said work-support comprising a top plate 16 and a vertical shank 17, integral therewith and projecting downwardly from the top 16 into a boss 18, formed upon the base 9. The shank 17 is prevented from rotating in the boss 18 by means of a set-screw 19 and is adjusted vertically therein by means of an adjusting-screw 20, screw-threaded into the base 9.

Upon the upper face of the top 16 of the work-support 15 a breast-gage 21 is fastened. The vertical flange 22 of said breast-gage is provided to limit the extent to which the boot-heel can be moved toward the right, Fig. 2, as it is fed into the machine, as hereinafter described. The horizontal flange 23 of said breast-gage is provided with slots 24 24 to receive the clamp-screws 25, screw-threaded into the top 16. Said top is further provided with two ears 26 26, screw-threaded to receive adjusting-screws 27, each of which bears against the horizontal flange 23 and forms an accurate means of adjusting the breast-gage. 85 toward the right and left, Fig. 1, or tangential to the rotary cutter 13. Upon the top 16 side gages 28 28 are also adjustably fastened by means of screws 29 29, projecting through slots 30 and having screw-threaded engagement with said top 16.

The vertical flange 22 is provided with a

curved depression 33 in its upper face of substantially the contour of the cutting edge of the rotary cutter 13 in transverse section, the breast of the heel being thus supported very close to the cutting edges of the rotary cutter. It will be noted that the supporting-surface upon the work-support for the bottom lift of the heel lies in a plane outside the periphery of the rotary cutter and that 10 said supporting-surface extends across outside the periphery of said cutter upon opposite sides of a median line transverse to the shaft 11 and intersecting the periphery of said cutter, and, further, it will be noted that 15 the face of the flange 22, against which the breast of the heel rests while the cutter is performing its work, provides a supporting-face located in a plane extending longitudinally of said shaft and adapted to hold the 20 breast of the heel in a plane extending longitudinally of said shaft.

The operation of the machine hereinbefore specifically described is as follows: The cutter 13 is rotated in the direction of the arrow, 25 Fig. 1. The heel is placed upon the top 16 of the work-support 15, with the top lift of said heel resting upon said top 16, and is fed forward by the operator between the side gages 28 until the breast of the heel comes in contact with the vertical flange 22 of the breast-gage 21. As the heel is thus being fed forward it will be seen that the rotary cutter will remove from the bottom lift of the heel upon the side of said bottom lift adjacent to 30 the breast of the heel a curved portion, leaving in the finished heel a curved depression 31. It will be noted that the top 16 is cut out at its front end upon a curve 32 in order that the operator may grasp the heel upon 35 the top and bottom thereof, and thus hold it firmly as it is fed along the top of the work-support and to the cutter. By loosening the set-screw 19 and turning the adjusting-screw 20 it is evident that the work-support 15 may 40 be raised or lowered, and thus increase or diminish, respectively, the depth and width of the curved depression 31. Said depression may be still further increased or diminished by adjusting the breast-gage toward the right 45 or left, respectively, as hereinbefore described. Different widths of heels may be accommodated by adjusting the side gages 28 toward or away from each other, Fig. 3.

Having thus described my invention, what 55 I claim, and desire by Letters Patent to secure, is—

1. In a machine for chamfering the bottom lift of a heel for boots and shoes, a rotary shaft, a cutter fast thereto, a work-support, 60 said work-support provided with a supporting-surface for said bottom lift lying in a plane extending longitudinally of said shaft

located outside the periphery of said cutter, and a breast-gage provided with a supporting-face located in a plane extending longitudinally of said shaft. 65

2. In a machine for chamfering the bottom lift of a heel for boots and shoes, a rotary shaft, a cutter fast thereto, a work-support, 70 said work-support provided with a supporting-surface for said bottom lift lying in a plane extending longitudinally of said shaft located outside the periphery of said cutter, a breast-gage provided with a supporting-face located in a plane extending longitudinally of said shaft, and means to adjust said work-support radially with relation to said rotary cutter. 75

3. In a machine for chamfering the bottom lift of a heel for boots and shoes, a rotary 80 shaft, a cutter fast thereto, a work-support, said work-support provided with a supporting-surface for said bottom lift lying in a plane extending longitudinally of said shaft located outside the periphery of said cutter, 85 and a breast-gage provided with a supporting-face adapted to hold the breast of a heel in a plane extending longitudinally of said shaft.

4. In a machine for chamfering the bottom 90 lift of a heel for boots and shoes, a rotary shaft, a cutter fast thereto, a work-support, said work-support provided with a supporting-surface for said bottom lift lying in a plane extending longitudinally of said shaft 95 located outside the periphery of said cutter, and a breast-gage provided with a supporting-face adapted to hold the breast of a heel in a plane extending longitudinally of said shaft, said supporting-face located upon opposite sides of a median plane transverse to said shaft and intersecting the periphery of 100 said cutter. 100

5. In a machine for chamfering the bottom lift of a heel for boots and shoes, a rotary cutter, a work-support, said work-support provided with a supporting-surface for said bottom lift lying in a plane outside the periphery of said cutter and a breast-gage fast to said work-support and adjustable thereon tangentially to said rotary cutter. 105 110

6. In a machine for chamfering the bottom lift of heels for boots and shoes, a rotary cutter, a work-support, and a breast-gage fast to said work-support, said breast-gage provided 115 with a curved depression in its upper face for the purpose specified.

7. In a heel-gouging machine, the combination of a curved gouging-knife, a heel-support having a rest for the heel-breast the edge of which is curved corresponding to the curvature of the knife, said rest terminating close to the path of movement of said knife, substantially as described. 120

8. In a heel-gouging machine, the combination of a circularly-moving curved gouging-knife, a heel-support having a rest for the heel-breast the edge of which is curved to correspond to the curvature of the knife, said rest terminating close to the path of movement of said knife, substantially as described.

In testimony whereof I have hereunto set my hand in presence of two subscribing witnesses.

JAMES W. SNELL.
